LIGHTING FIXTURE FOR GASOLINE PUMPS

Robert V. Fredericks, 201 SW. 30th St.,
Fort Lauderdale, Fla.

Filed June 8, 1960, Ser. No. 60,874

Term of patent 3½ years

(Cl. D48—31)

FIGURE 1 is a side elevational view of a lighting fixture for gasoline pumps showing my new design, with a light tube shown in broken lines for illustrative purposes only.

FIGURE 2 is a side elevation thereof as seen from the right of FIGURE 1,

FIGURE 3 is a side elevation thereof as seen from the right of FIGURE 2,

FIGURE 4 is a bottom plan view thereof,

FIGURE 5 is a top plan view thereof, and,

FIGURE 6 is a horizontal section taken on line 6—6 of FIGURE 2.

I claim:

The ornamental design for a lighting fixture for gasoline pumps, as shown and described.
